J. A. DAINOFF.

COMPOSITE BLANK AND METHOD FOR GOLD AND SILVER LEAF SIGN LETTERS AND
ORNAMENTS FOR GLASS.

APPLICATION FILED APR. 27, 1914.

1,116,803.

Patented Nov. 10, 1914.

UNITED STATES PATENT OFFICE.

JULIUS A. DAINOFF, OF NEW YORK, N. Y.

COMPOSITE BLANK AND METHOD FOR GOLD AND SILVER LEAF SIGN-LETTERS AND ORNAMENTS FOR GLASS.

1,116,803.

Specification of Letters Patent. Patented Nov. 10, 1914.

Application filed April 27, 1914. Serial No. 834,689.

To all whom it may concern:

Be it known that I, JULIUS ABRAHAM DAINOFF, a subject of the Czar of Russia, and a resident of the borough of Brooklyn, in the city of New York, county of New York, and State of New York, have invented certain new and useful Improvements in Composite Blanks and Methods for Gold and Silver Leaf Sign-Letters and Ornaments for Glass, whereof the following is a specification.

The object of this invention is to avoid the difficulties and reduce the time required for the formation of gold and silver leaf lettering on windows and other similar surfaces.

This invention relates to composite blanks for gold or silver leaf sign letters, characters or ornaments, easily applicable by an unskilled person to the glass of a window or door pane or other article to form a sign or ornament thereon.

Figure 1 of the accompanying drawings represents a perspective view of one embodiment of this invention, this illustration being in the form of a composite sign letter blank ready for application to the glass. Fig. 2 represents a composite sheet blank from which composite sign letter and ornament blanks have been cut. Fig. 3 represents a rear elevation of a pane of glass having a composite metal leaf sign letter blank applied thereto in reverse position, showing the temporary backing of the blank under process of removal. Fig. 4 represents the front elevation of a pane of glass having applied thereto a sign letter from one of these composite blanks, showing a border of a permanent backing applied to the letter and extending beyond the metal leaf. Fig. 5 represents a vertical section on line 5—5 of Fig. 4 showing a letter from one of these blanks applied to the glass and covered with a permanent backing of paint. Fig. 6 represents a perspective view of a fragment of a glass pane having one of these composite letter blanks applied thereto, this figure showing the temporary holding sheet which is used in applying the letter blank to the glass. Fig. 7 is a perspective view similar to Fig. 6, showing the temporary holding sheet partially pulled off and the temporary

backing of the metal leaf letter coming off with said holding sheet.

The same reference numbers are used in all the figures to indicate the same parts.

An embodiment of this invention comprises a backing 1 and a layer 2 of metal leaf superposed thereon to which is preferably added another layer 3 of metal leaf. 60

The backing 1 consists of a thin sheet of absorbent material preferably composed of ordinary tissue paper, newspaper or the like. A coating of refined oil preferably olive oil is applied to a sheet of the paper designed to form the backing and the so coated sheet is allowed to stand for ten minutes more or less until the oil soaks into the body of the paper. Then a sheet of gold or silver leaf 2 is applied to the oiled paper sheet and adheres thereto. Then a second sheet 3 of gold or silver leaf is applied over the sheet 2 and adheres thereto. A slight pressure is applied to the superposed layers and they adhere together. Then a portion of the three-ply 75 sheet, or two-ply sheet as the case may be, corresponding in shape to the desired letter or other character or design is cut or stamped out. The cut out portion constitutes a composite blank containing gold or silver leaf letters, characters or ornamental devices ready for application to the window or other place of use. 80

These composite layers or other characters or ornaments may be placed on the market as articles of manufacture or supplied by order of the users. 85

In the application of a letter, character or ornament contained in the cut out composite blank to the glass 10, a holding sheet 90 or strip 40 is preferably attached by some adhesive matter at two or three points as indicated at 5 to the composite blank. This strip projects at opposite ends or opposite sides beyond the body of the cut out composite blank and the projecting ends can be grasped by the operator for placing the letter or other device on the glass. 95

The back of the glass pane where the lettering or other device is to be applied is prepared in the usual manner of preparing panes for the application of gold leaf in its crude state, namely, by a weak solution of gelatin and boiled water. Then each com-

posite blank containing a letter or other device is grasped by the holding sheet 4 and placed in position with its metal leaf letters, or ornaments against the pane. The letters, characters or ornaments so placed with their backings and holding sheets adhering thereto are allowed to dry on the glass for a period of from five to thirty minutes according to the condition of the atmosphere. After the so applied letters or other devices are sufficiently dry, the holding sheet 4 and the backing sheet 1 are pulled off simultaneously from each as indicated in Fig. 7, or the backing sheet may be pulled off separately as indicated in Fig. 3. An application of benzin to the back of the holding sheet 4 or backing 1 will facilitate the removal thereof.

After the holding sheet and backing are removed a coating of paint 6 is applied by means of a brush to the back of the letter and a shading or complete border may be formed on the glass beyond the gold leaf as indicated in Fig. 4. A paint of any color may be used for this purpose. This coating of paint protects the letter and secures its permanency on the glass.

These composite blanks for letters or other characters or ornamental designs may in some cases be practical when made with one layer of metal leaf or with more than two layers thereof, but two layers of the leaf are preferable, as one layer will cover any defects or pin holes in the other.

These composite blanks for gold and silver sign letters, ornaments, and the like are economical to manufacture, prevent waste of gold or silver leaf and avoid loss of time. By their use the sign letters or other ornaments can be applied and finished at one time; whereas in the ordinary application of gold or silver leaf letters two or more visits on different days are required. Moreover these composite blanks enable the letters or other designs to be easily applied to skylights or other places where it is difficult for the painter to design and paint the individual letters.

I claim as my invention:

- 50 1. A composite blank for sign letters, characters or ornaments comprising a backing composed of an absorbent sheet of paper or similar material containing a refined oil, and a sheet of metal leaf adhering thereto.
- 55 2. A composite blank for sign letters, characters or ornaments comprising a backing composed of an absorbent sheet of paper or similar material containing a refined oil,

and two superposed layers of metal leaf adhering to each other and to said oiled backing.

3. The method of making a composite blank for metal leaf letters, characters or ornaments which consists in applying refined oil to an absorbent sheet of thin paper and allowing the oil to soak into the paper, and then placing the oiled paper in contact with a sheet of metal leaf, whereby said leaves will adhere together.

4. The method of making a composite blank for metal leaf letters, characters or ornaments which consists in applying refined oil to an absorbent sheet of thin paper and allowing the oil to soak into the paper, and then placing the oiled paper in contact with a sheet of metal leaf, whereby said leaves will adhere together, and then applying a second layer of metal leaf over the first.

5. A metal leaf character or ornament blank comprising a backing composed of an absorbent sheet of paper or similar material containing a refined oil, and a sheet of metal leaf adhering thereto.

6. A metal leaf character or ornament blank comprising a backing composed of an absorbent sheet of paper or similar material containing a refined oil, and two superposed layers of metal leaf adhering to each other and to said oiled backing.

7. The method of making a metal leaf character or ornament blank which consists in applying refined oil to an absorbent sheet of thin paper, allowing the oil to soak into the paper, placing the oil soaked paper in contact with a sheet of metal leaf and permitting said oiled paper and metal leaf to adhere by attraction, and then cutting out the character or ornament blank from the so adhering sheets.

8. The method of making a metal leaf character or ornament blank which consists in applying refined oil to an absorbent sheet of thin paper, allowing the oil to soak into the paper, placing the oil soaked paper in contact with a sheet of metal leaf and permitting said oiled paper and metal leaf to adhere by attraction, applying a second layer of metal leaf over the first, and then cutting out the character or ornament blank from the so adhering sheets.

JULIUS A. DAINOFF.
